DOOR OR WINDOW MOUNTING

Charles Edward Fuller, Dothan, Ala.

Application June 6, 1942, Serial No. 446,109

3 Claims. (Cl. 16—147)

The present invention relates to new and useful improvements in doors and windows of the swingable type, and has for its primary object to provide, in a manner as hereinafter set forth, a closure of this character comprising a novel construction and arrangement whereby said closure is hingedly supported at opposite edges and may be swingably opened from either edge and thereafter closed by returning the door to the starting closed position.

Another very important object of the invention is to provide a swinging door or window of the aforementioned character comprising unique means for automatically and positively locking either hinged edge of the closure to the frame while the other edge is in an outswung position.

Other objects of the invention are to provide a door or window of the character described which will be comparatively simple in construction, strong, durable, highly efficient and reliable in operation, compact, and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is an elevational view, looking at one side of a swinging door embodying the present invention.

Figure 2 is an elevational view, looking at the opposite side thereof.

Figure 3 is a view in horizontal section, taken substantially on the line 3—3 of Figure 1.

Figure 4 is a perspective view of one of the hinges.

Figure 5 is a perspective view of one of the spring pressed latches.

Figure 6 is a view in horizontal section, taken substantially on the line 6—6 of Figure 1.

Figure 7 is a view substantially similar to Figure 6 but showing the door partially open.

Figure 8 is an enlarged fragmentary view in horizontal section, taken substantially on the line 8—8 of Figure 1 and showing, in top plan, one of the spring latches.

Figure 9 is an enlarged fragmentary perspective view of one of the hinges.

Figure 10 is an enlarged fragmentary perspective view of one of the edges of the door, showing one of the spring latches thereon.

Figure 11 is a top plan view of one of the telescopic holders or braces.

Figure 12 is a view in front elevation of one of the telescopic holders or braces.

Figure 13 is an enlarged fragmentary view in vertical section; taken substantially on the line 13—13 of Figure 3.

Referring now to the drawings in detail, it will be seen that the embodiment of the invention which has been illustrated comprises a door frame which is designated generally by reference numeral 1 for the reception of a horizontally swinging door 2.

As shown in broken lines in Figures 3 and 6 of the drawings, the vertical edges of the door are separably and hingedly connected to the corresponding jambs 3 of the frame 1. Door supporting hinges 4 are mounted on the upper and lower portions of the jambs 3. One leaf of each supporting hinge 4 is in the form of a hook 5 which is engageable in a socket 6 formed in one side of the door adjacent the edge of the door, as indicated in Figures 6, 7 and 8 of the drawings, for supporting the door on the jambs 3. The hook leaf 5 corresponds in width to the space between the upper and lower pin barrels 8 of the hinge 4, and the pin barrels project outwardly from the jamb and toward the door as clearly indicated in the drawings.

Suitable spring latches 7 are mounted on the edges of the door 2 in positions to engage behind one of the pin barrels 8 as the door is opened from the opposite edge, whereby the hinging edge of the door is prevented from coming off the hooks 5 and hence from falling from the supporting hinges by movement of the door relative to the hooks in a direction toward that side of the door at which the opening movement takes place. As shown particularly well in Figures 8 and 10 of the drawings, the latches 7 consist of flat springs secured at one end to a lateral portion of the edge of the door and extending toward the opposite side of the door, the unattached portion of the spring being curvilinearly spaced from the edge of the door in a manner to cause the free ends of the latches to snap behind the pin barrels 8 as the door pivots from a closed position toward an open position as indicated in Figure 8.

Extensible braces or holders 9 are provided for the upper and lower portions of the door 2. The holders 9 have one end fixedly secured to the hinges 4 at 10 and their other ends hingedly secured, as at 11, to one side of the door and adjacent the opposite edge thereof, said holders including telescopic male and female sections 12 and 13, respectively. Stop and set screws 14 in

the male sections 12 are slidable in longitudinal slots 15 which are provided therefor in the female sections 13 of the holders 9.

Hinged striker plates or keepers 16 are recessed in the jambs 3 between the upper and lower hinges 4. Projecting from the hinged ends of the swinging striker plates 16 are cams 17 the purpose of which will be presently set forth. As seen in Figure 4 of the drawings, the recesses which accommodate the hinged striker plates 16 are indicated at 18.

Plates 19 are secured on the edge portions of the door 2. Latches or bolts 20 are pivotally mounted on the plates 19 to operate in chambers 21 which are provided therefor in the edges of the door 2, said latches being engageable with the free ends of the hinged striker plates 16. Suitable springs 22 yieldingly urge the latches 20 toward projected or operative position. Handles 23 are provided on the pivoted ends of the latches 20 for retracting said latches. Hooks 24 project from the outer ends of the plates 19. The hooks 24 are engageable behind the upper and lower pin barrels 25 of the hinged striker plates 16 and said hooks are adapted to swing with said striker plates above and below the stationary attaching plates or leaves 26 thereof. Further, the lower hooks 24 are engageable with the cams 17 for swinging the striker plates 16 outwardly into engagement with the latches 20 when the door 2 is closed.

Slidably mounted on the door 2 and extending between the latches 20 is a rod 27. The rod 27 is provided, on its ends, with heads 28 (see Fig. 13) for engagement by the latches 20, said heads including arms 29 which rest on said latches. Thus, the latches 20 are operatively connected to each other for positive actuation to projected or locking position.

It is thought that the operation of the device will be readily apparent from a consideration of the foregoing. Briefly, with both of the latches 20 in projected position, as seen in Figure 3 of the drawings, the door 2, which is now supported by all of the hinges, is positively secured in closed position against swinging movement from either edge. To open the door from either edge, the corresponding latch 20 is retracted against its spring 22 through the medium of its handle 23. When this occurs, the rod 27 is actuated for positively projecting the other latch and holding same in projected or locking position. The edge of the door which has thus been freed may be swung open, said door pivoting or hinging on the hinges at the other or still latched edge. As the door opens, the spring latches 7 at the pivotal edge of the door, which are engaged behind the lower pin barrels of the adjacent hinges 4, secure said door on the members 8 of said hinges. When the door is closed, the latch 20 on the free

edge thereof moves inwardly and clears the adjacent pivoted striker plate 16 and is projected by its respective spring 22. At this point the lower hook 24 on the adjacent plate 19 engages 5 behind the cam 17 and swings the striker plate 16 outwardly into the path of the adjacent latch 20. The extensible holders 9, in addition to assisting in supporting the door, may also function as means for frictionally securing said door in any desired position.

It is believed that the many advantages of a door or window constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

20 What is claimed is:

1. A frame structure comprising spaced jambs, a closure engageable between said jambs, said closure having sockets therein, hooks pivotally mounted on the jambs and engageable in the sockets for pivotally or detachably connecting either edge of the closure to the jambs, means for releasably securing the closure on the hooks, and longitudinally extensible braces mounted on the hooks and having one end hingedly secured to the closure.
2. A frame structure comprising a pair of spaced, vertical jambs, a vertical door engageable between said jambs, hinges mounted on the jambs, said hinges including swinging hooks, the door having sockets therein for the reception of the free end portions of the hooks for pivotally or detachably connecting either vertical edge of the door to the jambs, telescopic braces having one end portion fixedly secured to the hooks and 35 their other ends hingedly connected to the door adjacent the remote vertical edges thereof, and means for releasably securing the door on the hooks.
3. A frame structure comprising a pair of spaced, vertical jambs, a vertical door engageable between said jambs, hinges mounted on the jambs, said hinges including swinging hooks, the door having sockets therein for the reception of the free end portions of the hooks for pivotally or detachably connecting either vertical edge of the door to the jambs, telescopic braces having one end portion fixedly secured to the hooks and 40 their other ends hingedly connected to the door adjacent the remote vertical edges thereof, and means for releasably securing the door on the hooks, the hinges further including eyes, said means comprising arcuate spring latches mounted on the vertical edges of the door and engageable 45 behind the hinge eyes.

CHARLES EDWARD FULLER.
